UNITED STATES PATENT OFFICE.

GEORGE W. PHINNEY, OF GUERNEVILLE, CALIFORNIA.

PLOW.

SPECIFICATION forming part of Letters Patent No. 449,331, dated March 31, 1891.

Application filed November 20, 1890. Serial No. 372,083. (No model.)

To all whom it may concern:

Be it known that I, GEORGE W. PHINNEY, a citizen of the United States, residing at Guerneville, Sonoma county, State of California, have invented an Improvement in Plows; and I hereby declare the following to be a full, clear, and exact description of the same.

My invention relates to an improved construction for plows; and it consists in providing the plow with a jointed beam, a means for turning the beam to one side or the other and maintaining a draft directly upon the point of the plow, to whichever side it may be turned.

In the accompanying drawings I give a more complete explanation of my invention. Figure 1 is a plan or top view. Fig. 2 is a side elevation.

20 A is the rear portion of the beam of the plow, to which the handles B, the standard C, and the plow D are attached in the usual manner.

25 At the point E the front portion F of the plow-beam is pivoted by means of a vertical pivot-bolt G, so that this front portion may be turned from one side to the other.

30 H H are jointed rods or links, the front ends of which are connected to the stout eyebolts I, which are fixed upon the front end of the beam. The rear ends of these links or rods, extending back one on each side of the plow-beam, are connected with a lever K, which is pivoted centrally beneath the rear and fixed portion A of the plow-beam. One end of this 35 lever is extended out so as to form a pawl or catch, as at K', and this is engaged by a curved notched rack L. This semicircular rack has its ends pivoted to the side of the beam A, so that it may be lifted up to disengage it from the lever-arm K' or pressed down to engage this arm when it has been turned to any point where it is desired to have it remain.

40 M is a lever fulcrumed to the rear end of the beam A, having one arm extending beneath the curved movable rack L, and the other arm is connected by a rod O with a lever P, fixed upon one of the handles B of the plow within easy reach of the plowman.

45 The operation will then be as follows: When 50 the plow-beam is set in a straight line, the lever K is locked so as to retain it in that position, and plowing will then be done in the

ordinary manner. If it is desired to throw the landside of the plow toward the vines or trees when plowing in a furrow, it is done by 55 first disengaging the curved rack L from the lever K, which operates the link-rods, and by turning this lever the front end of the plow-beam is thrown around to the right, which throws the landside of the plow toward the 60 left of the line of draft, the lever-arm K' being then locked in place by dropping the curved rack to engage it. The draft upon the forward end of the plow-beam will pull through the right-hand jointed rod, so that 65 the draft will be in a straight line and the pull will come upon this rod. This enables the plowman to throw the plow as far to the left as may be desired, while at the same time keeping the horse in the furrow. If it is de- 70 sired to throw the plow in the other direction, it is done by turning the front end of the beam in the same manner as before described to the left side, and when it is locked in this position the draft will come upon the left-hand 75 jointed rod in the same manner as described in the first instance. By this arrangement the plow is very easily adjusted and caused to travel nearer to or farther from the lines of the vines or trees, the horse may travel at any 80 point desired in the furrow, and the draft will be maintained in a straight line through the medium of the rods. By reason of the joints in the rods, which correspond with the joint in the beam, it will be seen that when the 85 beam is turned to either side the rod which is on the outer side will bend at the joint and lie around the outside of the beam, while the inner rod will form a cord across the inside of the curve or angle formed by the beam, and 90 the draft will act in a straight line and directly upon this rod. Each of the rods is screw-threaded at the rear end and fits into the coupling end H', which connects it with the lever K, so that by screwing the rods into 95 or out of the coupling they may be shortened or lengthened to give them the proper tension and length.

Having thus described my invention, what I claim as new, and desire to secure by Letters Patent, is—

1. A plow having the beam jointed so that the front end may turn about a vertical axis with relation to the rear portion, a lever ful-

- erumed to turn in a horizontal plane upon the rear portion of the beam, flexible connections extending from the opposite ends of said lever to corresponding sides of the front 5 and movable portion of the beam, and a device for holding the lever so that the beam may be turned to either side and maintained at an angle with the rear portion, substantially as herein described.
- 10 2. In a plow, the beam having a joint in its length about which the front portion may be turned from side to side, a lever fulcrumed to the rear portion of the beam so as to turn in a horizontal plane, jointed or flexible rods 15 having the front ends connected with opposite sides of the front portion of the plow-beam and the rear ends connected with corresponding ends of the lever, and a movable latching device adapted to engage the lever so 20 that the front end of the beam may be turned to either side by the movement of the lever and retained at an angle with the rear portion, substantially as herein described.
3. In a plow, the beam having a joint in its 25 length about which the front portion turns in a horizontal plane, a lever fulcrumed to the rear portion of the beam, flexible rods connecting the ends of said lever with the front portion of the beam so that by move- 30 ment of the lever the beam may be turned to

one side or the other, coupling ends by which the rods are united with the lever, and screw-threaded connections for the same, whereby the rods may be lengthened or shortened, and the latch or holding device by which the lever is engaged so as to retain the beam at either side of the central line and throw the draft upon the inner rod, substantially as herein described.

4. In a plow, a beam having a joint in its 40 length about which the front portion turns in a horizontal plane, a lever fulcrumed to the rear portion, flexible adjusting-rods connecting the front portion of the beam with the ends of the lever so that the beam may 45 be bent to either side by moving said lever, a curved rack hinged to the rear portion of the beam and adapted to engage and hold the lever in any position, a lever-connecting rod, and hand mechanism whereby the hinged 50 rack may be disengaged from the lever so as to allow it to move and the beam to be turned, substantially as herein described.

In witness whereof I have hereunto set my hand.

GEORGE W. PHINNEY.
